(57) **CLAIM**

The ornamental design for a coin bin, as shown and described.

DESCRIPTION

The product is a removable bin for receiving coins in a self-service coin handling machine.

FIG. 1 is a right, top, front perspective view of a coin bin according to our new design;

FIG. 2 is a front elevational view thereof;

FIG. 3 is a right side elevational view thereof, the left side elevational view being a mirror image thereof;

FIG. 4 is a rear elevational view thereof;

FIG. 5 is a top plan view thereof; and,

FIG. 6 is a bottom plan view thereof.

The broken lines represent environmental structure and form no part of the claimed design.

1 Claim, 5 Drawing Sheets
